CLAIM

The ornamental design for a poultry feeder, as shown and described.

DESCRIPTION

FIG. 1 is a perspective view of a poultry feeder showing my new design;

FIG. 2 is a right side elevational view thereof, the left side elevational view being a mirror image thereof;

FIG. 3 is a front elevational view thereof;

FIG. 4 is a rear elevational view thereof;

FIG. 5 is a top view thereof; and,

FIG. 6 is a bottom view thereof.
